F. H. COLPITTS

APPARATUS FOR LIFTING WATER, GRAIN, OR THE LIKE

Filed June 9, 1920

UNITED STATES PATENT OFFICE.

FAWCETT H. COLPITTS, OF DENVER, COLORADO, ASSIGNOR TO HYDRO VACUUM ELEVATOR COMPANY, OF DENVER, COLORADO.

APPARATUS FOR LIFTING WATER, GRAIN, OR THE LIKE.

Application filed June 9, 1920. Serial No. 387,714.

To all whom it may concern:

Be it known that I, FAWCETT H. COLPITTS, a citizen of Great Britain, residing at Denver, in the county of Denver and State of Colorado, have invented certain new and useful Improvements in Apparatus for Lifting Water, Grain, or the like, of which the following is a specification, reference being had to the accompanying drawings.

10 My invention relates to elevating apparatus involving the use of centrifugal force.

An object of this invention is to provide an apparatus involving a plurality of outwardly slanting open-ended conduits having a rotary movement about a vertical axis around which they are equidistantly arranged.

15 A further object of this invention is to provide in an apparatus of the above described character certain improvements in the construction and arrangement of its parts which by utilizing the inertia of liquid to be lifted and tapering or attenuation 20 of a column of liquid, attain to a maximum capacity with the expenditure of minimum motive energy and speed.

25 A further object of this invention is to combine in a single means the advantages severally attainable, viz, to utilize the inertia 30 of the liquid to be lifted to initiate the lifting movement and to establish tapering or attenuation of an inclined column of liquid in an elevating conduit as contra-distin- 35 guished to a column of liquid filling the entire conduit.

40 My invention consists in the construction, arrangement and combination of elements hereinafter set forth, pointed out in the 45 claims and illustrated by the accompanying drawing, in which—

45 Figure 1 is a vertical sectional view of one form of my apparatus. Figure 2 is a top plan view of the same. Figure 3 is a detail sectional view of one of the conduits.

In the construction of the apparatus as shown, the numeral 10 designates a supporting frame, of any suitable form, extending to any desired height and at its lower end entering a body of water. The lower end of the supporting frame 10 is provided with a base 11 and a vertical shaft 12 is stepped on said base by ballbearings 13, having a protective cover 14 carried by a sleeve 15.

50 Mounted on the shaft 12 are collars 16, 55 17 and attached to these collars are outwardly extending arms 18. The uppermost arms 18 are of greater length than the lowermost arms and conduits or pipes 19, in this instance four in number, are mounted in 60 and supported by said arms. The conduits or pipes 19 are inclined radially of the vertical shaft 12 and preferably are located equidistant therefrom. The lower end portion of each conduit or pipe 19 is formed 65 with an inlet opening 20 of substantially the same diameter as the conduit, the inlet openings of all of the pipes opening in the direction of travel or rotary movement thereof. 70

The centers of the inlet openings 20 are in the axial planes of the conduits and fall in a common circle concentric with the axis of the shaft 12. The upper end of each conduit or pipe 19 is closed by a rearwardly 75 curved surface and also is formed with an outlet opening 21 disposed reversely with relation to the opening 20. That is to say, the outlet openings 21 of the several conduits 19 open rearwardly relative to the rotary motion or direction of travel of the several conduits. The centers of the outlet openings 21 are in the axial planes of the conduits and fall within a circle concentric with the axis of the shaft 12 of larger diameter 80 than the circle relative to the intake openings 20. The upper end portion of the frame 10 supports the upper end of the shaft 12 in an anti-friction bearing 22, carrying a pulley 23 whereby power may be applied from any suitable source to rotate the shaft 12 at high speed in the direction of the arrow indicated. Extending around the upper ends of the elevating conduits or pipes 19 and disposed slightly below the horizontal 85 plane of the outlet openings thereof, is an annular trough 24 having a discharge chute 25 extending tangentially therefrom, a separating wall 26 forming the inner wall of the discharge chute and extending in a 90 direction concentric to the center of the trough.

95 When the element consisting of the shaft 12, arms 18 and conduits 19, is rotated in the direction of the arrow in Figure 2, the 100 movement of the lower ends of the conduits beneath the level of the liquid in the source of supply causes the liquid to enter through

the intake openings 20 and rise in the conduits to a height determined by the velocity of the element.

Owing to the inertia of the supply of liquid and the radially slanting position of the conduits and the position of their discharge openings in a common circle and rearward with relation to the direction of rotation, the liquid is moved upwardly and out of the conduit into the trough 24, partly by centrifugal force, partly by the tendency of the liquid to continue to move in a straight line and partly by the tendency of the liquid to fall and come to rest at the outlet openings 21 of the conduits.

In upward and radial travel in each conduit the column of liquid becomes tapered or attenuated and flattened out into segmental form in cross-section on the rear walls of the conduits so that it does not fill or fully conform to the cross-section of any conduit, and is discharged by the outlet openings 21 into the trough.

This apparatus does not require priming. When rotated the conduits will engage the liquid or other matter and raise it to the desired extent and discharge it into the trough under two major conditions, viz, the radial inclination of the conduits and the velocity or rotary speed thereof, modified by two minor conditions, viz, the forwardly opening uniform inlet ports having their centers in the axial planes of the conduits, and the rearwardly opening outlet ports of uniform diameter having their centers in the axial planes of the conduits.

I claim:-

1. An elevating machine of the character described comprising an element mounted for rotation about a vertical axis and including a plurality of continuously straight conduits slanting upwardly and outwardly from said axis, each conduit having at its

lower end an intake opening having its center in the axial plane of the conduit and facing in the direction of rotation of the element and at its opposite end a discharge opening having its center in the axial plane of the conduit and disposed in the circle of rotation of said end and rearwardly of the same with relation to the direction of rotation.

2. An elevating machine of the character described comprising an element mounted for rotation about a vertical axis and including a plurality of nonangular conduits slanting outwardly from said axis, each conduit having at its lower end an intake opening having its center in the axial plane of the conduit and facing in the direction of rotation of the element and at its opposite end a discharge opening having its center in the axial plane of the conduit and disposed in the circle of rotation of said end and rearward of the same with relation to the direction of rotation.

3. An elevating machine of the class described, comprising an element mounted for rotation about a vertical axis and including a plurality of straight conduits and slanting upwardly and outwardly from said axis, each conduit having at its lower end an intake opening having its center in the axial plane of the conduit and facing in the direction of rotation of the element, and at its upper end a discharge opening having its center in the axial plane of the conduit and in the circle of rotation of said end and rearwardly of the same with relation to the direction of rotation, said straight tubes having end walls and presenting interior concave surfaces opposite said openings.

In testimony whereof I hereunto affix my signature.

FAWCETT H. COLPITTS.
